FURNACE FUEL CONTROL

Joseph O. Thorsheim, Minneapolis, Minn., assignor to Minneapolis-Honeywell Regulator Company, Minneapolis, Minn., a corporation of Delaware

Application April 5, 1948, Serial No. 19,120

4 Claims. (Cl. 137—405)

1

This invention relates to a furnace fuel control for regulating the flow of oil to an oil burning furnace. More particularly, the invention is concerned with a control device which provides for a low rate of fuel flow to maintain a pilot flame in the furnace and at least one other larger rate of fuel flow to provide high fire operation of the furnace.

There are numerous control devices which provide the above-mentioned furnace operation but many of them perform in an unreliable manner. Those which rely on the metering of fuel through a small orifice to provide low fire operation of the furnace, probably give the least reliable performance. This is usually due to the gumming of the small orifice.

One of the objects of this invention is to provide a furnace fuel control which will provide an extremely low and uniform rate of fuel flow for maintaining a pilot flame in the furnace, without having the fuel flow through a small passage or orifice.

Another object of the invention is to provide a control which uniformly and regularly delivers a metered charge of fuel to a furnace.

A further object of the invention is to provide a control which delivers metered charges of fuel to the furnace and which has means for varying the size of the charges.

A still further object of the invention is to provide a control which has a valve associated therewith which will cut off the flow of fuel if one or more of a plurality of undesirable conditions arise.

Another object of the invention is to provide a control having a simple means for manually opening a safety valve therein and to reset a condition-responsive valve-actuator therefor.

Another object of the invention is to provide a compact control having fuel metering means and a safety valve with concealed passages connecting them.

Still further objects of the invention will become apparent upon reading the following detailed description of the invention in conjunction with the accompanying drawings wherein:

Figure 1 is an elevational view of the control with portions thereof broken away;

Figure 2 is a plan view of the control with its cover removed and portions thereof broken away;

Figure 3 is a cross-sectional view of the safety valve of the control;

Figure 4 is a cross-sectional view of an accumulator in the control, taken on line 4—4 of Figure 1;

2

Figure 5 is a cross-sectional view of a control valve in the control, taken along line 5—5 of Figure 1 and with parts thereof broken away and removed;

5 Figure 6 is a cross-sectional view of the above-mentioned control valve taken along the bearing plane surface of the valve;

10 Figure 7 is a plan view of a power adjusting means for the accumulator with portions thereof broken away and the accumulator shown in cross-section;

15 Figure 8 is a sectional view taken on line 8—8 of Figure 1; and

Figure 9 is a sectional view taken on line 9—9 of Figure 1.

20 The furnace fuel control comprises a wall member, generally designated by the reference numeral 11, adapted to be secured to a furnace by any suitable means (not shown) or to a rigid support positioned in the vicinity of the oil burning furnace. The wall consists of a thick plate 12 having a plurality of grooves formed in the inner surface thereof and which terminate in bores extending from the bottom of said grooves through the plate to the outer surface thereof. The functions of these grooves will be described hereinafter. Another thinner plate 13 is clamped to plate 12 by means of a plurality of screws (not shown) with a sheet of any suitable gasket material 14 therebetween. It is thus seen that the grooves in the plate 12 and the gasket material 14 form the walls of passages adapted to conduct fuel oil from one of the above-mentioned bores to another.

25 Secured to the wall 11, against the outer face of plate 12 and at the right hand end thereof, as viewed in Figures 1 and 2, is a filtering unit 15. It consists of a casing 16 enclosing a wire mesh filter 17, a fuel inlet tapping 18 and an outlet bore 19. The details of the filter unit form no part of this invention. It may take the form of most any conventional filter.

30 Mounted on the outer surface of plate 12 adjacent the filter unit, by means of screws 20, is a safety shut-off valve generally designated by the reference number 21. As can best be seen in Figure 3, the safety valve comprises a housing 22 having a cone-shaped chamber 23 at its inner end terminating in an axial bore 24. A slot 25 extends from the lower edge of the housing 22 upwardly into the bore 24 and from the outer edge of the housing 22 inwardly to a point spaced from the chamber 23. Extending vertically through the outer portion of the housing 22 and 35 intersecting the slot 25 is an elongated opening

26. A diaphragm 27 is positioned between the housing 22 and a ring 28. All three of these elements are secured to the plate 12, with a gasket washer 29 therebetween, by means of the above-mentioned screws 20. A valve 30 is secured to the center portion of the diaphragm 27 by means of a threaded stem thereon passing through an aperture in said diaphragm and into threaded engagement with a plunger 31 slidably mounted in the bore 24. The plunger 31 has a diametrical slot 32 therein and an extension of reduced diameter at its outer end. A spring 34 resiliently urges the plunger 31 inwardly to normally seat the valve 30 in a terminal bore of passage 35. The passage 35 establishes communication between the outlet 19 of filter unit 15 and a chamber 36 between the diaphragm 27 of safety valve 21 and plate 12. The outlet from chamber 36 will be described below. Pivoted in the slot 25, on pivot 37, is a bell crank lever 38 having an actuating arm 39 and a power arm 40. The arm 40 extends into the slot 32 for actuation of the plunger 31.

Vertically slidably in opening 26 is a bar 41 having an aperture 42 therein through which the outer end of arm 39 extends. Slidably mounted on the bar 41 is a manually operable latch member 43 that is best seen in Figure 1. Slots 44 and 45 therein enable the member 43 to slide over thicker washers 46 and between the heads of bolts 47 and 48 and the bar 41. A tension spring 49, anchored to the lower end of member 43 and the bolt 48, normally urges the member 43 upwardly with respect to bar 41 to position the pin 47 against the lower end of slot 44. This provides a lost motion connection between the members 43 and 41 for resetting purposes. A laterally extending arm 50 on the latch member 43 has a transversely bent shoulder portion 51 and a vertical slot 52. A notch 53 in the lower left hand edge of the member 43, as viewed in Figure 1, is adapted to cooperate with a bell crank lever latch 56 to hold the valve 30 open, the spring 49 being stronger than the spring 34. A pivot 54 extends through the upper ends of the legs of a U-shaped arm 55 of the bell crank lever and through slot 52, and is rigidly secured to plate 12. The slot 52 merely enables the latch member to move downwardly over the pivot 54 to reset the latch as described hereinafter. The spring biased lost motion connection between the members 43 and 41 provides a resilient strain release connection between the manually operable latch member 43 and the valve 30 through the bar 41, lever 38 and plunger 31, so that the latch member can continue to move after the valve has opened fully, to permit this resetting action. A spring 55a may also be provided between the outer end of arm 55 and a fixed portion of the control, to partially balance the weight of a float to be presently described. The outer end of the other arm 57 of the bell crank lever 56, is pivoted to the upper end of a stem 58 which, in turn, is secured at its lower end to a float 59.

A trough or drain 60 has a float chamber 61 positioned substantially centrally thereof, a well 62 receiving the lower end of the filter unit 15, and drain surfaces 63 and 64 converging downwardly and sloping toward the back to the top of float chamber 61. The drain 60 is secured to plate 12, with a gasket or cement therebetween, by means of screws (not shown). The drain 60 also has a threaded outlet opening 65 and a bore 66 extending laterally from said opening 65 through the rear wall of the chamber 61 or drain 75 sufficient to allow a slight amount of play of the

60 to align with a terminal bore of a grooved passage 66a in the plate 12. The other terminal bore of passage 66a is positioned above chamber 61. A bore 67 extends through the bottom portion of the side wall of the float chamber 61 to align with a terminal bore of an inverted, U-shaped, grooved passage 67a in plate 12. This passage loops over the passage 66a and connects with outlet 65 through a passage 84, to be described below, and bore 66.

Positioned near the center of the control, above the drain 60 and to the left of the valve 21, is an accumulator generally designated by the reference numeral 68. As can best be seen in Figure 4 of the drawing, the accumulator comprises a base member 69 having a recessed portion 70, a diaphragm 71, a piston 72 which is biased by means of a spring 73 toward the base member 69, a guide ring 72a, and an adjustable stop member 74. The accumulator is secured to the plate 12 by means of screws 75 with a gasket 76 therebetween. An opening 77 through the gasket 76 establishes communication between the recess 70 of the accumulator and a terminal bore of a passage 82 (described below) in plate 12. It is thus seen that when the adjustable stop 74 is screwed outwardly, oil under pressure may flow into recess 70 and move the diaphragm and piston 72 outwardly into engagement with the end of stop 74. When fuel pressure is relieved, the spring 73 may then force the piston 72 and diaphragm 71 toward member 69 and discharge fuel oil from recess 70.

The means for controlling the flow of fuel oil to and from the accumulator 68 comprises a rotary control valve 78, best seen in Figure 5. It has three radially extending grooves 79 communicating through concentrically spaced slots 80 in a sleeve-like bearing member 81 with a terminal bore of passage 82. The bearing member extends into the bore and rotates therein. The passage 82 is the one that communicates with chamber 70 of the accumulator 68. The outer end of the grooves 79 are each adapted to successively pass over the terminal bores of passage 83 and passage 84 (see Figure 1). These terminal bores are spaced apart a distance greater than the width of the grooves 79 and are less than 120° apart. This assures that only one of these terminal bores can be in fluid flow engagement with a groove 79 at a time. The passage 83 leads to a terminal bore communicating with chamber 36 in the safety valve 21. The passage 84 leads to a terminal bore in alignment with bore 66 to establish communication with the outlet 65. A boss on the outer surface of the control valve 78 is slotted at 85 to receive a drive plate 86.

The drive plate 86 is driven by a flanged coupling 87 having a slot 88 in a boss thereon, similar to the slot 85. A coil compression spring 89 surrounds the bosses on the members 78 and 87 and the drive plate 86 to hold them in axial alignment and to urge the valve 78 away from the coupling 87 and into engagement with plate 12. The coupling 87 has a slot in the opposite wall thereof at right angles to the slot 85. This slot is engaged by a tongue 91 of a drive shaft 92. The drive shaft 92 is rotated at a constant speed by means of a gear train (not shown) which in turn is driven by a synchronous motor (not shown) enclosed in the housing 93. The motor housing 93 is mounted on the plate 12 by means of bolts 94 extending through spacing sleeves 95. The distance of the housing 93 from the plate 12 is sufficient to allow a slight amount of play of the

drive plate 86 in the slots 85 and 88, but is sufficiently close so as to keep the spring 89 under enough compression to maintain the valve 78 in oil sealing engagement with the surface of plate 12. It will be noted that the screw-threaded, adjustable abutment 74 is threaded through a lateral projection 93a extending from a side wall of the motor casing 93. Current is supplied to the motor through leads 92a.

Modification

In the modification of the accumulator shown in Figure 7, the piston 172 has a laterally extending stem 172b which slidably fits in an axial bore 96 of a plunger 97. The plunger 97 slidably fits in the open end of an inverted, cup-shaped member 98. The member 98 has a diametrical slot therethrough providing a slot 99 on one side and a much longer slot 100 on the other side. An axial bore in the closed end of the cup-shaped member 98 receives the unthreaded end of a threaded adjustment screw 14a which is threaded through a fixed support 93b. Extending through the slots 99 and 100 is a wedge-shaped plate 101 which, in operation, bears against one end each of slots 99 and 100 and the end of plunger 97, to limit the outward movement of the piston 172. The large end of the plate 101 is connected by means of a screw 102 to a bimetallic strip 103. A slot (not shown) in the bimetallic plate permits the passage of the screw 102 and allows for longitudinal movement of the screw and plate 101 with respect to the bimetallic strip. This enables the side edges of the plate 101 to properly bear against the ends of slots 99 and 100 and the end of plunger 97. The position of the head of the screw 102 with respect to the adjoining surface of the bimetallic member, permits, if desired, a slight amount of movement of the bimetallic member in one direction and then the other direction before the plate 101 is moved. One end of the bimetallic member is secured to a lateral projection 104 on the plate 12a, while the center portion of the bimetallic member carries a resistance heater 105 that is adapted to be energized through a room thermostat (not shown) by a source of electrical energy (not shown). The room thermostat may be of the on-off type or may be of the potentiometer type. The first would give a two-position operation of the plate 101 while the second would provide a many-position operation thereof.

Operation

The device is shown in its operating position in Figures 1, 2 and 3, that is, with the float in its lowered position, the safety valve open and the adjustable abutment in a position to permit the diaphragm of the accumulator to move outwardly against the bias of spring 73 under oil supply pressure. As the synchronous motor constantly rotates the control valve 78 at a uniform speed, registration of the end of one of the grooves 79 with a terminal bore of passage 83 will permit the flow of fuel through the filter unit 15, passage 35, valve 21, passage 83, control valve 78, and passage 82 to the chamber 70 of the accumulator 68. This permits the oil under its supply pressure (gravity or pump) to force the diaphragm and the piston against the abutment to accumulate or store a metered charge of the fuel oil. Continued movement of the control valve will first cut off communication between the chamber 70 and the oil supply and then establish communication between the chamber and the fuel outlet 65 leading to the furnace. The discharge

is accomplished by the groove 79 in the control valve registering with the terminal bore of passage 84 which leads to the outlet 65 through bore 66. The provision of three grooves 79 in the control valve causes three accumulations and discharges for each complete rotation of the control valve.

By adjusting the adjustable abutment or stop outwardly, the rate of fuel flow may be increased inasmuch as a greater volume of fuel oil will be accumulated every time the accumulator is put into communication with the source of fuel supply. This may be done either manually by rotating the screw-threaded abutment 74 in Figure 4 or automatically by the room thermostat causing the energization of the resistance heater 105 to cause warping of the bimetal in the direction of the arrow shown in Figure 7.

The control will continue to deliver fuel at a uniform rate at whatever abutment setting is provided. This will be true even for the minimum flow rate in that fuel oil does not have to flow through a small metering orifice or passage but by periodic surges of fuel through relatively large openings. This prevents the clogging of the fuel passages and, therefore, provides trouble free and uniform operation of the furnace.

Figure 4 shows the abutment 74 in its no-flow position, with the piston and diaphragm held against the base member 69 by the adjustable abutment 74. In this position no dischargeable fuel can be accumulated or discharged, as the piston 72 and diaphragm 71 cannot move outwardly under the oil supply pressure against the bias of spring 73.

Should the flame in the furnace become extinguished, the fuel oil will accumulate in the furnace to only that level which will cause the fuel oil to back up into the discharge opening 65, through bore 66, through passage 66a and into chamber 61. This will cause the float 59 to be raised to disengage latch arm 55 from the notch 53 in latch member 43. As soon as the latch member 43 is freed, the spring 34 in the safety valve will move the valve 30 into seating engagement with the terminal bore of passage 35 and raise the bar 41 and the latch member 43 to their elevated positions by means of the bell crank lever 38.

The same safety action would take place if any one or all of the units mounted on the plate 12 started to leak. For example, if the diaphragm 71 in the accumulator should spring a leak, the oil escaping around the piston would be caught by the upwardly and outwardly inclined surfaces 63 and 64 which would direct the oil into the float chamber 61. It is thus seen that if any condition should arise that would possibly cause the flooding of oil over the area of the furnace installation, the safety valve would automatically be tripped by the float mechanism to shut off the flow of fuel.

To reset the device after the furnace has been conditioned for operation, the upper end of the latch member 43 is manually moved downwardly to first cause the bell crank lever 38 to open the valve 30, against the bias of spring 34, and then to slide the member with respect to the bar 41, against the tension of spring 49, to bring shoulder 51 into engagement with arm 57, pivotally connected to the float 59 through stem 58. Further downward movement forces the float to the bottom of chamber 61. As the float 59 is substantially the same diameter as chamber 61, fuel oil 75 will be forced outwardly through bore 67 to prime

the siphon passage 67a connected to the passage 84 adjacent the outlet bore 66. This will cause rapid discharge of the fuel oil from the chamber 61 to the furnace or, if desired, to waste, if the conduit to the furnace is disconnected. Lowering of the arm 57 also brings the arm 55 into a vertical movement path of the bottom edge of notch 53 so that, the releasing of latch member 43, will not cause the lifting of bar 41 to close the valve 30 but engagement of the bottom edge of the notch 53 with the bottom of arm 55.

While the preferred embodiment of this invention has been described above, it is apparent that various modifications may be made therein without departing from the spirit of the invention. Therefore, it is to be understood that the scope of the invention is to be determined not by the above specific disclosures, but by the appended claims.

I claim as my invention:

1. A furnace fuel control comprising a substantially vertical wall having inlet and outlet passages formed therein, a valve mounted on said wall for controlling the flow of fuel through said passages, a float chamber secured to said wall under said valve and having upwardly and outwardly inclined drain surfaces, a fuel feeding means mounted on said wall above said drain surfaces and connected to said inlet passage, a passage in said wall providing communication between an upper portion of said chamber and a lower portion of said outlet passage, an inverted U-shaped passage in said wall providing communication between the bottom of said chamber and a lower portion of said outlet passage and having the bridge of said U-shaped passage above said chamber, a float of slightly smaller diameter than said chamber pivotally connected to a bell crank lever having a latch thereon, and manually operable means for opening said valve and forcing said float downwardly in said chamber whereby fuel is forced into said U-shaped passage to prime it and cause the discharge of fuel from said chamber, said manually operable means having a strain release connection with said valve and a laterally extending arm for engaging said bell crank lever and an abutment thereon for engaging said latch only when said float is in its lowered position in said chamber.

2. In a control device for supplying fuel to a furnace and having a vertical wall with inlet and outlet passages therein, the combination comprising fuel feeding means on said wall, a biased closed safety valve mounted on said wall for controlling the flow of fuel through said device, latch means for actuating said valve to its open position against its bias, said latch means having a resilient strain release connection with said valve to permit continued movement thereof beyond the open position of said valve, a float chamber on said wall and having drain surfaces extending laterally from the top thereof and beneath said valve and fuel feeding means, a pas-

sage in said wall between said outlet and an upper portion of said chamber, an inverted generally U-shaped passage in said wall having a short leg thereof terminating in a lower portion of said chamber and a longer leg thereof terminating in said outlet at a lower level, a float of slightly smaller width than said chamber and positioned therein, and pivoted latching means connected to said float and engageable with said latch means to hold said valve open when said float is low in said chamber and disengageable from said latch means when said float is high in said chamber to cause closing of said valve.

3. A safety float chamber for a fuel control device comprising, a chamber, an adjoining wall extending upwardly beside and beyond the upper edge of said chamber for supporting a plurality of fuel control means above said chamber, an inverted generally U-shaped passage formed in said wall with the lower end of one of the legs of said passage terminating in a lower portion of said chamber and the lower end of the other leg terminating in a discharge passage of said device at a lower level than the bottom of said chamber, and another passage formed in said wall extending from said discharge passage to a portion of said chamber.

4. A safety control device comprising, a chamber, an adjoining wall extending upwardly beside and beyond the upper edge of said chamber, a plurality of fuel controlling means mounted on said wall above said chamber, an inverted generally U-shaped passage formed in said wall with the lower end of one of the legs of said passage terminating in a lower portion of said chamber and the lower end of the other leg terminating in a discharge passage of said device at a lower level than the bottom of said chamber, and another passage formed in said wall extending from said discharge passage upwardly between said legs to a top portion of said chamber.
